UNITED STATES PATENT OFFICE.

DANIEL E. HENNESSY, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

BEAD-FORMING DEVICE.

Application filed January 12, 1924. Serial No. 685,818.

This invention has to do with the forming of straight side beads and particularly the application of flipper strips to the bead core. Machines for this purpose hitherto suggested are objectionable in that they tend to distort the bead and produce a defective product. This I believe is in part due to improper support of the bead core and it is therefore one of the objects of my invention to provide a machine in which the bead or bead core is uniformly supported, in horizontal position, during the applying operation thereby preventing distortion of the bead as the strip is applied and the subsequent wrinkling and buckling of the strip.

Another object is to so apply the strip that air pockets will not be formed between the strip and the bead core, and to provide folding mechanism to accomplish such application.

Another object is to provide a machine equally efficient in operation on all sizes of beads.

Other objects will appear in connection with the detailed description of my invention.

One embodiment of my invention is illustrated in the accompanying drawings in which

Figure 1 represents a front elevation of the device with the strip guiding means omitted.

Figure 2 represents a plan view,

Figure 3 represents an end elevation,

Figure 4 is a detail view of certain of the applying rolls, and

Figures 5, 6, and 7, illustrate successive steps in the application of the flipper strip to the bead core.

In the drawings 1 designates the frame of the machine. Mounted in suitable bearings upon one end of said frame is a shaft 2 provided at its inner end with a roll 3, the inner portion of which is beveled. Directly above said roll and co-operating therewith is a roll 4 rotatably mounted on the end of arm 5 rigidly mounted on rod 6 which in turn is rotatably mounted in bearings 7.

On the opposite end of frame 1 and slideable thereon is positioned a bar 8, provided at each end with threaded lugs 9 which ride on screws 10. Screws 10 are carried in brackets 11 mounted on the frame 1 and are provided at their outer ends with hand wheels 12. As is obvious, by rotating hand

wheels 12, bar 8 may be adjusted longitudinally of frame 1.

Mounted on suitable bearings on bar 8 and in alignment with shaft 2 is a shaft 13 provided at its inner end with a beveled roll 14 similar to roll 3. Directly above roll 14 and co-operating therewith is a roll 15 rotatably mounted on the end of arm 16 rigidly secured on rod 17, which is rotatably carried in bearings 18 mounted on bar 8. Rolls 4 and 15 are each provided with grooves 65 which in co-operation with the beveled portions of rolls 3 and 14 provide triangular openings adapted to receive and grip a triangular or straight side bead core 19 at substantially diametrically opposite points 70 as is clearly shown in Figures 1 and 2. Rolls 4 and 15 are adapted to be raised, to admit and release the bead cores, through links 20 and 21, respectively connected at their upper ends to arms 5 and 16. The lower end of link 20 is pivotally connected to lever 22 pivoted at its center point to a bracket 23 secured to frame 1. The other end of lever 22 is connected to the upper end of rod 24 the lower end of which is connected to foot 80 pedal 25 pivoted at 26 to frame 1. A spring 27 connected to lever 20 and frame 1 yieldingly holds roll 4 in contact with roll 3. In a similar manner link 21 is connected at its lower end to one end of a lever 28 pivoted to bracket 29 secured to bar 8, the other end of lever 28 being connected to foot pedal 25 by rod 30 which is provided with turnbuckle 31 to accommodate its length to the various positions of bar 8. Roll 15 is yieldingly held 90 in contact with roll 14 by spring 32 secured between link 21 and a bracket 33 secured to bar 8.

Adjacent roll 3 and positioned to underlie the bead core is a roll 35 rotatably mounted on inclined shaft 36 secured to frame 1. Roll 3 is grooved to receive the lower interior angular edge of the bead core. Adjacent roll 35 and rotatably mounted at the end of arm 37 is a vertical beveled roll 38. Arm 37 is rigidly secured to rod 6 to move therewith. Co-operating with roll 38 is a roll 39 rotatably mounted on bracket 40 secured to frame 1. The beveled portion of roll 38 and the vertical surface of roll 39 are adapted to receive the upper interior angular edge of the bead core as is clearly shown in Figure 4, said rolls being slightly

spaced to permit passage of the upstanding edge of the flipper strip.

Rigidly secured to rod 17 and movable therewith is a guide 41, adapted to overlie the bead core and turn the flipper strip into position to be acted upon by rolls 14 and 15 as hereinafter described.

Freely rotatable rolls 42 and 43 are mounted on the frame 1 to underlie the bead core and support the same during the application of the flipper strip.

Carried by bracket 44 bolted to the frame 1 is a guideway 45 adapted to present the flipper strip in position to be applied to the bead. Said strip may preferably be supplied from a suitable roll of material 46 carried in arms 47 secured to the outer end of guide 45.

Rolls 3 and 14 are positively driven to feed forward the bead core and associated flipper strip in the following manner. A shaft 48 is mounted in suitable bearings in the lower part of frame 1. Said shaft is provided with pulleys 49 and 50 connected by belts 51 and 52 to pulleys 53 and 54 mounted respectively on the outer ends of shafts 2 and 13. Pulley 50 is elongated to accommodate the adjustment of bar 8 in the manner before mentioned and belt 52 is crossed in order that roll 14 may rotate in a direction opposite to that of roll 3. Power is applied to shaft 48 through pulley 55 which forms one member of a friction drive, the other member of which comprises a pulley 56 mounted upon the shaft of motor 57. Motor 57 is carried upon a lever 58 pivoted to the frame 1 at 59. The forward end of lever 58 forms a foot pedal 60 by means of which pulley 56 is forced into contact with pulley 55 to thereby impart motion to shaft 16. The pulleys 55 and 56 may be kept normally separated in any suitable manner as by placing the pivot 59 so that the weight of the motor maintains said pulleys separated except when pedal 60 is depressed, as shown in Figure 3. The upward movement of lever 58 may be limited by stop 62 suitably attached to the frame of the machine to overlie lever 58 as shown in Figure 1.

The operation of the device is as follows:

Bar 8 having been adjusted to the desired position, rolls 4 and 15 together with their associated members 38 and 41 are turned to raised position by means of pedal 25. The operator then inserts an annular bead core with the flat face resting upon beveled rolls 3 and 14 and supporting rolls 42 and 43. Pedal 25 is then released permitting rolls 4 and 15 to engage and grip the bead core. The strip of flipper material is then drawn along guide 45 and inserted beneath the bead core on the beveled roll 3 with the edge portions of said strip extending on either side of the core. Rotary movement is then imparted to rolls 3 and 14, through the agency of

foot pedal 60, and the bead core is thereby rotated drawing the flipper strip therewith, said strip being pressed against the under face of the core as the assembly is drawn between rolls 3 and 4. As the bead core and associated flipper strip passes over roll 35 the groove in said roll engages angular edge 63 of the core pressing the flipper strip firmly against said angular edge and partly bending the strip upwardly and along the interior circumferential face of the bead core as shown in Figure 6. This partial application of the flipper strip to the face of the bead progressively from the angular edge 63 prevents the entrapping of air between the flipper strip and the bead. The progressive movement of the core and flipper strip carries the same between rolls 38 and 39. The latter roll completing the application of the flipper strip to the interior face of the bead core as shown in Figure 7, roll 38 holding the bead core firmly against roll 39 during this operation. Progressive movement of the core and flipper strip brings the upstanding edge portion of the latter under guide member 41 which bends said portion of the flipper strip outwardly and over angular edge 64 of the bead core. The core and flipper strip then enter between rolls 14 and 15, the groove of the latter roll laying said strip over the inclined outer face of the bead as shown in Figure 5, while the cylindrical portions of rolls 14 and 15 press the overlapping edge portions of the flipper into firm smooth contact as shown at 65. Continued rotation of the bead completes the application of the flipper strip over the entire circumference of the core whereupon foot pedal 60 is released to disconnect shaft 48 from the motor. Foot pedal 25 is then depressed thereby raising rolls 4 and 15 with their associated members, permitting removal of the completed bead. The provision of supporting means at substantially uniformly spaced points together with the positive gripping action of rolls 3 and 4 and rolls 14 and 15 prevent distortion of the bead core during application of the flipper strip. By carrying out the application of the strip to the core in two separate operations with the mechanism therefor spaced a substantial distance apart, the distorting tendencies are minimized and tend to counterbalance each other. The provision of grooves in the folding rolls so formed as to engage the angular edges of the bead core permits the application of the flipper strip progressively around the cross section of the core, and the applying pressure, being first applied at the angular edges, prevents entrapment of air between the strip and the core.

It is obvious that my invention may be embodied in other forms than that shown and the machine disclosed is intended to be illustrative only.

I claim:

1. In a device of the character described means for folding a web about an endless angular core comprising a plurality of 5 grooved rolls adapted to engage the angular edges and adjacent faces of the core to progressively apply the web longitudinally around the core, said rolls being adapted to support said core at substantially diametrically opposed points.

2. In a device of the character described means for folding a web about an endless angular core comprising a plurality of 15 grooved rolls adapted to engage the angular edges and adjacent faces of the core to progressively apply the web longitudinally around the core, said rolls being adapted to grip the core at substantially diametrically opposed points and movable to release said 20 core.

3. In a device of the character described, means for folding a web about an endless angular core, comprising two sets of grooved 25 rolls adapted to engage the angular edges and adjacent faces of the core to progres-

sively apply the web longitudinally around the core, said rolls being adapted to support said core at substantially diametrically opposed points, and means for adjusting said sets of rolls toward and away from each other to accommodate different sized cores. 30

4. The method of applying a flipper strip to an annular bead core which comprises applying the flipper strip about the core in successive steps at points substantially equally spaced about the entire circumference of 35 the bead core.

5. The method of applying a flipper strip to an annular bead core which comprises applying the flipper strip about a portion of 40 the cross sectional periphery of the core at one point of the annulus and completing the application thereof at a point on the annulus substantially diametrically opposite the point of first application, while the core is 45 maintained in an undistorted condition.

In testimony whereof, I have signed my name to the above specification.

DANIEL E. HENNESSY.
